GEORGE C. JENSEN, OF OAKLAND, CALIFORNIA.

MECHANISM FOR LOCKING LEVERS FULCRUMED FOR UNIVERSAL SWINGING MOVEMENT.

1,385,552.

Specification of Letters Patent. Patented July 26, 1921.

Application filed December 7, 1917. Serial No. 206,083.

To all whom it may concern:

Be it known that I, GEORGE C. JENSEN, a citizen of the United States, residing at Oakland, in the county of Alameda and State of California, have invented certain new and useful Improvements in Mechanism for Locking Levers Fulcrumed for Universal Swinging Movement, of which the following is a specification.

10 The present invention relates to an improved mechanism for locking levers, and said invention relates more particularly to a type of lock mechanism wherein a longitudinally movable lock controlled locking bolt is adapted to engage a portion of the lever to lock the same from operative movement within its mounting; to provide a construction wherein the lock controlled locking bolt is automatically held in locked position 20 on being manually moved into such position and is automatically released on the release of the lock controlled mechanism coöperating therewith; to provide a construction wherein the locking bolt and its coöperating lock mechanism is formed as a part of the body providing a fulcrum point and closure for the lower portion of the lever. The invention consists broadly in providing a lever capable of movement in different horizontal 30 planes and coöperating with which is a bifurcated locking bolt longitudinally movable into and out of coöperative relation with the lever and having associated therewith a suitable locking pawl or member for 35 engaging the bolt to retain the same in coöperative relation with the lever, to lock the lever from operative movement.

With the above mentioned and other objects in view, the invention consists in the 40 novel construction and combination of parts hereinafter described, illustrated in the accompanying drawings and pointed out in the claim hereto appended; it being understood that various changes in the form, proportion, size and minor details of construction within the scope of the claim may be resorted to without departing from the spirit or sacrificing any of the advantages of the invention.

50 To more fully comprehend the invention reference is directed to the accompanying sheets of drawings, wherein—

Figure 1 is a central longitudinal sectional view of the preferred embodiment of my

lock as applied to any well known type of 55 motor vehicle gear shift lever.

Fig. 2 is a sectional view taken on line 2—2 of Fig. 1 and viewed in the direction of the arrows, illustrating more clearly the speed gate for controlling the operative 60 movement of the lever.

Fig. 3 is a sectional view taken on line 3—3 of Fig. 1 and viewed in the direction of the arrows.

In the drawings, the reference numeral 1 65 designates a lever of a type commonly used on motor vehicles, at the upper end of which is a handle, not shown in the drawings. Said lever 1 is arranged for swinging movement in two parallel planes and for this purpose is freely fulcrumed upon a horizontal shaft 3, the latter being fixed in the fixed arms or brackets 5 extending upwardly from a tubular housing or member 2, supported in any suitable manner and inclosing that 75 portion of the lever below its fulcrum point.

While I have illustrated the type of lever fulcrumed on a shaft, it is to be understood that my locking device is not confined to this type of lever, but is applicable to any type 80 of lever fulcrumed for swinging movement in two parallel planes.

The lower end 6 of the lever 1, as illustrated in Fig. 1 of the drawings, is flattened or enlarged for engagement with the 85 shifter rods or blocks of a sliding gear mechanism, said shifter rod and mechanism being well known in the art, and are therefore not illustrated in the drawings.

The usual spring for holding the lever 1 90 in its vertical position laterally, is illustrated at 7, Fig. 1 of the drawings, to normally maintain the lower end of the lever when in neutral position in the opening 8 between the meeting ends of arms 8', the 95 opening 8 being so disposed as to necessitate a transverse movement of the lever to neutral position before the same can be moved laterally for operation in different parallel planes one at each side of the arms 8', as 100 in Fig. 1 of the drawings.

It will thus be apparent that the arms 8' and opening 8 provide a speed gate for guiding the lever in its movement and it will also be apparent that the end 6 of said lever 105 is of such size as to prevent the upward withdrawal of the lever through the opening 8 should the shaft 3 be removed, the lock

mechanism hereinafter described, preventing axial movement of the lever to admit of the same being withdrawn from the opening 8.

5 Slidably mounted in a guide 10 formed in the side wall of the tubular housing 2 and communicating with the interior thereof at a point below the fulcrum point of the lever and preferably immediately above the speed 10 gate is a locking plunger 11 bifurcated at its outer end as at 12, said plunger being adapted to engage the lower portion of the lever 1 when said portion is received in the opening 8 and thus prevent lateral movement of the lever on its fulcrum. The plunger 11 normally lies in its retracted position due to the tension of a spring 13, one end of which abuts against the rear wall 14 of the plunger and the other end abuts against the 15 headed end 15 of a guide member 16 which is carried by the rear wall of the guide 10 and extends into a spring receiving opening or bore 17 formed axially of the rear portion of said plunger 11. The plunger carries 20 at its rear end a laterally extending operating member 18 projecting outwardly through a slot 19 in the upper wall of the bore 11 and is adapted to be pressed forwardly when it is desired to force the plunger outwardly and lock the lever from movement when in its neutral position.

To automatically lock the plunger when moved into engagement with the lever, a lock barrel receiving bore 20 is provided, 35 communicating with the plunger guide 10, and in the lower end of the same is positioned a vertically reciprocating latch member 21 provided with a flange 22 and carrying a tongue 23 operating in a vertical guide 40 24 which prevents the latch from rotating on the operation of the locking barrel 25.

A spring 26 interposed between the base 45 of the barrel 25 and the flange 22, maintains the latch in contact with the upper surface of the plunger 11. The latch 21 carries a lug or finger 27 on its under-face and which is adapted to be forced by the spring 26 into a suitable opening 28 in the upper surface of the rear portion of the plunger 11, 50 when said plunger is forced forwardly to lock the lever, the lug or finger preventing the release of the plunger until such time as a controlling key, not shown, is employed to rotate the locking barrel.

55 The latch member is provided with a suitable cup 29 for receiving the lower end 30 of the barrel 25, and said cup is provided in its side wall with a substantially triangular cam slot for receiving the latch releasing pin 31 on the lower end 30 of the barrel 25.

When in interlocked position, the pin 31 lies at the junction of the vertical wall A and horizontal wall B of the cam slot, enabling the spring 26 to force the latch downwardly into locked position relatively 65 to the plunger 11, when the plunger is forced forwardly to lock the lever from movement.

When the latch is in its depressed locking position, the pin 31 is at the upper end of 70 the wall A so that an oscillatory movement of the barrel approximately a one-quarter revolution, first in an anti-clockwise and then in a clockwise direction, first causes the pin 31 to travel over the downwardly inclined wall C of the cam slot which raises the latch, permitting the plunger to automatically release, due to the spring 13, from engagement with the lever 1 and thus move the pin 31 to the full line position as in Fig. 80 1 of the drawings, which enables the bolt to automatically lock the plunger on the next forward movement thereof.

It will be apparent that I have provided a construction wherein the locking bolt on 85 being manually moved linearly into engagement with the lever to prevent movement of the same is on engaging the lever locked in such position, and on the operation of the locking means said plunger is automatically 90 moved rearwardly longitudinally from engagement with the lever, permitting free movement thereof.

Having thus described my invention, what I claim as new and desire to protect by Letters Patent is:—

In combination with a support, a lever, and means with which said lever co-operates for preventing movement of the lever comprising a plunger in said support adapted 100 to engage said lever and at least partially surround the same, means for normally retaining said plunger in disengaged position away from the lever, a lock adapted to engage a part carried by the plunger to retain 105 the same in engaged position with the lever, and an operating member for the plunger having a projecting part accessible to the operator and interengaged with the plunger and the support to maintain the plunger and 110 its locking part in aligned position relative to the lock and the lever.

In testimony whereof I have signed my name to this specification in the presence of two subscribing witnesses.

GEORGE C. JENSEN.
